UNITED STATES PATENT OFFICE

2,165,740

FOOTWEAR

Eugene B. Ward, West Springfield, Mass.

Application October 23, 1937, Serial No. 170,637

2 Claims. (Cl. 36—71)

This invention relates to improvements in footwear and is directed more particularly to improvements in means adapted to be associated with a shoe for supporting a certain part of the 5 foot, namely the metatarsal arch.

The principal objects of the invention are directed to the provision of a simple yet efficient support for a certain part of the foot in all natural positions thereof and according to this invention, the support provided therefor is adapted to support the foot both when the foot is relatively flat, as in standing, and when it is bent or flexed, as in walking.

Broadly the device of this invention includes a 15 relatively-stationary shank member and a movable member which is actuated by the sole of the shoe so that when the sole of the shoe is bent, as it is in walking, the movable member is urged upwardly so as to be as closely adjacent the part of the foot it is desired to support as it is when the sole is substantially flat, as it is in standing.

According to the preferred form of the invention, the device includes but two parts which are 25 so connected together and so arranged that one part is moved relative to the other by the bending or flexing of the sole of the shoe as the wearer bends the foot. In this way the supporting part automatically moves with the shoe and foot 30 so as to automatically assume a supporting position at all times.

The device of the invention in its broad aspects is adapted for use in connection with shoes of all types and sizes. While it may vary somewhat 35 in form in order to be adapted for use in different shoes, it is essentially a two-part device arranged as will later be described and it is simple in construction so as to be economical to manufacture yet it is positive and efficient in operation.

40 Various other novel features and advantages of the invention will be more fully hereinafter referred to in connection with the accompanying description of the invention in the form at present preferred and reference will be had to the 45 accompanying drawing, wherein:

Fig. 1 is a plan view of the device of the invention with dot-dash lines to indicate the preferred position thereof with relation to a foot;

Fig. 2 is a partial side elevational view of the 50 forward end portion of the device shown in Fig. 1, with dot-dash lines to indicate the preferred position thereof with relation to the sole of a shoe;

Fig. 3 is a partial plan view of the device shown 55 in Fig. 1;

Fig. 4 is a side elevational view of the part shown in Fig. 3;

Fig. 5 is a side elevational view with dot-dash lines to indicate the preferred position of the device with relation to the shoe and foot; 5

Fig. 6 is a plan view of a modified form of the device of the invention; and

Fig. 7 is a transverse sectional view to illustrate that the device may be curved or arched for its supporting function. 10

Referring now to the drawing more in detail, the invention will be fully described.

A human foot, represented by dot-dash lines F in Fig. 1, has metatarsal heads, as indicated by H. The metatarsal arch, the region of the 15 foot which I desire to support, is just rearwardly of the heads H.

A shank member is represented by 2 and this is for extending upwardly adjacent the longitudinal arch of the foot. With respect to Figs. 20 1-4 inclusive the device is shown as an appliance to be placed in a shoe of common manufacture and, in this case, the member 2 overlies the shank commonly found in shoes. The shape thereof may vary but it preferably has a forward 25 end portion curved slightly as shown in Figs. 2 and 5.

A support member 4 is hingedly connected to the member 2 and the manner of connection may take various forms. In the form shown, the 30 shank 2 is provided with a pair of slots 6 located inwardly from the forward end thereof and the rear end of the part 4 is provided with offset lugs such as 8 which extend into the slots, as shown more clearly in Fig. 3. 35

The parts 2 and 4 are of such lengths and are so hingedly connected that the forward end portion of part 4 is forward of the forward extremity of part 2. Thus, the forward end portion of part 4 is adapted to rest on the sole portion of the shoe 40 indicated by X in Fig. 2.

Thus, it will be seen, as the sole X bends, as it does in walking, the sole, being in engagement with the said forward end portion of part 4 moves the latter upwardly against the metatarsal arch 45 of the foot.

Where the device is an appliance to be placed within a shoe as just described, there may be a covering C of flexible material, such as leather, secured to the plate 2, as by rivets shown. 50

Now I will describe the form shown in Figs. 5 and 6.

This form of the device is adapted to be built in the shoe and 2' represents the shank which all 55 shoes must have. It will be noted that this is

somewhat longer than the shank member 2 which is a part of the appliance shown in Figs. 1-4 inclusive, although the forward end thereof is located at the same point with relation to the sole X of foot F', as shown in Fig. 5. S in Fig. 5 represents a shoe in which the device is built.

A support member 4', similar to part 4 previously described, is hingedly connected to the upper side of part 2'. Again this hinged connection may take various forms but, for purposes of description, slots 6' in plate 2' and lugs 8' on plate 4' are shown in Fig. 6 with the parts arranged as described with reference to Figs. 3 and 4.

The usual shank built unto a shoe has a strengthening rib and this is shown at 3' in Fig. 6. It is to be understood, however, such a rib is not essential to the efficient operation of my device.

With either form, the support extends beyond the forward end of the shank so as to be in operative engagement with the sole X of the shoe. Then when the sole is bent, the support member, 4 or 4', is moved upwardly on its hinged connection.

As indicated in Fig. 7, the member 4 or 4' is preferably somewhat spoon-shaped. This is to conform more or less to the shape of the metatarsal arch of the foot.

While I have described the invention with great detail, what it is desired to secure by Letters Patent of the United States is:

1. As a new article of manufacture, a two-part device for use in a shoe to support the metatarsal arch of the foot comprising in combination, an elongated shank member adapted to rest on and extend along the longitudinal arch of the sole of a shoe with its forward marginal edge

disposed just rearwardly of the metatarsal arch of the foot when the shoe is worn, a convex plate member of rigid metallic material having its rear portion overlying the forward part of said shank member and its forward portion projecting forwardly beyond said forward marginal edge of the shank member so as to extend under the metatarsal arch of the foot when the shoe is worn, and a hinge connection between said rear portion of the convex member and the forward part of the shank member, all adapted and arranged whereby when the sole of the shoe is flexed as in walking it causes the convex member to move upwardly relative to the shank member against the metatarsal arch of the foot.

2. As a new article of manufacture a two-part device for use in a shoe to support the metatarsal arch of the foot comprising in combination, an elongated shank member adapted to rest on and extend along the longitudinal arch of the sole of a shoe with its forward marginal edge disposed just rearwardly of the metatarsal arch of the foot when the shoe is worn, said shank member being provided with a transverse slot adjacent its forward end, and a plate member of rigid metallic material having its rear portion overlying the forward part of said shank member and its forward portion projecting forwardly beyond said forward marginal edge of the shank member so as to extend under the metatarsal arch of the foot when the shoe is worn, the rear marginal edge portion of the plate member being offset and inserted into said slot, all adapted and arranged whereby when the sole of the shoe is flexed as in walking it causes the plate member to move upwardly relative to the shank member against the metatarsal arch of the foot.

EUGENE B. WARD.
